APPARATUS FOR USE IN THE DELIVERY OF LIQUIDS FROM CONTAINERS

Bryan James Todd, Robert Edmund Turner, and Robert E. Broberg, Wellington, New Zealand, assignors to Associated Motorists Petrol Company Limited, Wellington, New Zealand

Application March 20, 1947, Serial No. 735,990
In New Zealand March 11, 1946

Section 1, Public Law 690, August 8, 1946
Patent expires March 11, 1966

7 Claims. (Cl. 222—400.7)

1

The invention relates to apparatus for use in the delivery of liquids from containers, under the action of compressed air, and in connection with which it is known to use apparatus provided with a liquid discharge or flow pipe with a valve controlled liquid outlet therefrom, adapted for insertion in a container and so as to extend therefrom; an air transfer pipe or passage fitted with an air injector and a non-return valve, adapted for connection through an air control valve with a source of compressed air, for directing the latter into the container, and operating means common to the liquid outlet control valve and the air admission control valve, so arranged that said control valves are enabled to be opened at the same time by the same operating means, or if found necessary, so that each valve may be opened without opening the other.

The type of apparatus before referred to, is more particularly intended for use in the delivery or dispensing of lubricating oil in relatively small quantities, from drums at automobile service stations and elsewhere, the apparatus being transferred from one drum to another, as the drums are emptied of their contents, and it is essential, where compressed air is being directed into the drums for the purpose of ejecting the contents therefrom, to see that a pressure head in excess of the safety limit, can not be built up in the drums, so as to avoid the possibility of accidents.

An object of the invention, is therefore, to provide means for ensuring that a pressure head in excess of a predetermined safety limit can not be built up in a container from which liquid is to be ejected, by the use of compressed air injected into the container, and further, to provide the means in such form, that unless deliberately and also illegally tampered with, said means can not be rendered inoperative for the purpose of ensuring that the safety pressure limit in the drums will not be exceeded.

Further objects of the invention are to effect economy in the use of high pressure compressed air by causing the injection of atmospheric air into the container along with the stream of air from the high pressure jet and thereby increasing the volume of air injected into the container in a given time. Time in raising the requisite level of pressure in the container is also saved.

2

Other objects of the invention, are to simplify and render more efficient the mechanism for operating the liquid outlet control valve and the compressed air admission control valve, to provide means for locking said valves against operation, and thereby render the apparatus incapable of being operated by unauthorized persons, and to facilitate the placing of receptacles in position to receive liquid from the apparatus, by the provision of a guide on the latter.

Apparatus incorporating the improvements provided by the invention comprises, a liquid discharge or flow pipe and dispensing head with a valve controlled liquid outlet therefrom, adapted for insertion in a container so as to extend therefrom; an air transfer pipe or passage fitted with a non-return valve, and an air injector having therein holes for admitting a proportion of air at atmospheric pressure to the compressed air stream, and atmospheric air leads to said holes from different surfaces of the injector, to admit atmospheric air during the period of induction of same, and to permit by-passing of surplus compressed air when the pressure in the container has reached the predetermined safe limit, before the supply of compressed air may have been cut off by an air admission control valve, said pipe or passage being provided for directing compressed air through the air admission control valve in the head to the container; a rocking lever on the head for operating both the fuel outlet control valve and the air admission control valve; a fixed hand grip, and a trigger for actuating the rocking lever, both on said head; lugs on the latter, and a pin for insertion in said lugs for preventing operation of said valves, and a guide on the head adjacent the liquid outlet, for receptacles placed below the latter.

40 In the accompanying drawing, in conjunction with which the invention will be more fully described,

Figure 1 is a general assembly view, partly in section, of apparatus of the kind referred to, having applied thereto, the improvements constituting the invention, and to be herein more particularly described,

Figure 2 being a front view, and

Figure 3 a plan view, of the oil dispensing head 50 of the apparatus,

Figure 4 a longitudinal sectional elevation, and Figure 5 an end view, both enlarged, of the air injector of the apparatus, and

Figure 6 a sectional plan view enlarged, taken on the line 6, 6 Figure 1.

As illustrated, the type of apparatus to which the improvements are applied, is provided with a liquid discharge or flow pipe 1 adapted for insertion in a closed liquid container 2, to extend to, or to near the bottom thereof, and also above same, said pipe 1 having externally of the container 2 and above the highest available liquid level therein, a valve controlled outlet 3 in the dispensing head 11 of the apparatus, for liquid to be discharged from the container 2.

Means for introducing compressed air into the container 2, comprise an air transfer pipe or passage 4 leading to the interior of the container 2 above the highest liquid level obtainable therein, from a chamber 3 (Figure 4) in the injector 23, and to which compressed air is admitted through a jet 6 and a co-acting Venturi arrangement, and past a non-return valve 7, the latter being provided to prevent the escape of air pressure from the container 2, other than what is utilised to discharge liquid therefrom.

The compressed air transfer pipe or passage 4, and the injector 23, can either be incorporated in, or be combined with the discharge or flow pipe 1 and its fittings, or be formed in or be provided by, fittings formed separately therefrom.

In one form of apparatus suitable for enabling compressed air to be utilised to dispense or cause liquid, such as lubricating oil, to be discharged from a container 2 in quantities as required, the liquid discharge or flow pipe 1 is passed through a stuffing box 10 or the like, fitted in a container 2, so as to extend downwards to the required depth therein, and also so as to extend above same to the height required.

The upper or external portion of the discharge or flow pipe 1, has fitted to the outer end of its horizontal portion, the dispensing head 11, which contains a downwardly discharging opening 3 controlled by the cone shaped or tapered valve 9 seating therein under the action of a spring 12 on the valve stem 13, and in compression between the valve body and the upper portion of the head 11.

According to the improvements, the stem 13 of the aforesaid cone shaped or tapered valve 9, is made to extend upwards through a gland 14 in the head 11, to a lever 15 centrally pivoted thereon, said lever 15 being forked at both ends, one of the forks being fitted with inwardly extending pins 15a which are entered in a circular groove in the stem 13 of the liquid outlet control valve 9, while the other forked end of said lever 15 passes upon the pin 16 provided to operate the air admission control valve 17, said last mentioned forked end having a degree of lost motion in each direction between collars or projections 18 on the valve operating pin 16 aforesaid. There are also provided on the head 11 a fixed hand grip 19 and a trigger 20, both of which are positioned and shaped for gripping and operation by a hand of the operator, so that a squeeze of the hand operates the trigger 20 to cause the liquid outlet control valve 9 to lift and permit liquid to be discharged through the apparatus, from the container.

The liquid outlet control valve 9, and the air admission control valve 17, are both actuated by the lever 15 adapted to be operated by the trigger 20, which is fitted on a spindle 21 journalled on

the head 11, the forked lever 15 being secured on the spindle 21 by means of a grub screw, to rock with the same and the trigger 20, so that the same squeeze of the hand opens both valves 9 and 17.

The first part of the movement of the trigger 20, when actuated by a squeeze of the hand, lifts the valve 9 and opens the outlet 3, following which the appropriate forked end of the lever 15 engages the lower collar 18 on the pin 16, and depresses the valve 17 to admit compressed air via the inlet 22 to the head 11, and from which it passes to the line 4, so that during the first part of the movement, with an air pressure obtaining in the container 2, liquid is ejected without admitting compressed air, and during the second part of the movement, compressed air is passed to the container at the same time as liquid is being ejected therefrom.

Sufficient lost motion is provided between the upper collar 18 on the pin 16, and the forked end of the lever 15, to permit the pin 16 to be depressed far enough to open the valve 17, without actuating the lever 15, whereby if desired, compressed air can be passed into the container 2 without opening the liquid control valve 9.

In order to lock the apparatus against operation, a lock pin 25 can be inserted in lugs 23a on the head 11, and over the stem 13 of the liquid outlet control valve 9, so as to prevent the latter from being raised off its seating, the lock pin 25 being provided with a head, and being secured in the lugs 23a by means of a padlock or the like passed through its outer end.

The lugs 23a through which the lock pin 25 is passed to prevent operation of the liquid control valve 9, can be the same lugs, or extensions from the lugs, in which the spindle 21 of the trigger 20, and the forked lever 15, is mounted.

The compressed air inlet 22 to the head 11 can be coupled with a suitable source of compressed air supply by conventional means.

The compressed air admission control is automatic in operation, in that under ordinary conditions of operation of the apparatus, it is not actuated separately, but operates with the fluid dispensing valve 9 in the dispensing head 11 when required, and admits a charge of low pressure compressed air equal to, or less than a predetermined maximum, which may be varied to give, with a suitable co-acting Venturi arrangement, an ultimate air pressure in the container 2, which may be necessary to suit any condition.

The rendering of the apparatus foolproof, under ordinary conditions of use, against the building up of an excess of air pressure in the container 2 and thereby creating conditions of danger, is performed by permitting the by-passing of surplus compressed air through radial holes 24 in the injector 23, when the pressure in the container 2 has reached the predetermined safety limit, before the supply of high pressure air may have been cut off at the air control valve 17.

These radial holes 24 also provide for the admission of atmospheric air for injection with the compressed air stream into the container 2 to build up the air pressure therein, to the predetermined safe limit, thereby enabling the volume of air injected into the container 2 in a given time to be increased, besides economising the use of the compressed air.

In order to guard against blockage of these radial holes 24 inadvertently, or to render deliberate blocking of same as difficult as possible, and thereby prevent the by-passing of surplus

high pressure compressed air when the pressure in the container 2 has reached the predetermined safe limit before the supply of high pressure compressed air may have been cut off at the air control valve 11, the holes 24 are made to open into air leads from different surfaces of the injector and which can comprise flutes or recesses 26 in the side external surface of the body of the injector 23, said flutes or recesses 26 in addition to opening through the side of the latter at each side of the holes, also open at their ends through a surface or surfaces at right angles to the side external surface aforesaid, the arrangement of holes 24 and flutes or recesses 26 being such that they can not be readily blocked or closed.

Provision is also made for facilitating the placing of a receptacle such as a bottle or the like in the correct position below the liquid outlet 3 to receive liquid discharged therethrough, by means of a centering guide 27 on the head 11, adjacent said outlet 3, and against which guide the mouth or neck of the bottle or the like, is placed to bring the latter into the correct position to receive liquid discharging through the outlet 3.

The guide 27 aforesaid is curved or rounded and can be fitted with resilient material, and may also be stepped or formed to accommodate bottles or the like of varying sizes.

What we do claim and desire to obtain by Letters Patent of the United States of America is:

1. Apparatus for use in delivering liquid from containers, wherein compressed air is injected into the latter for the purpose of ejecting liquid therefrom, comprising a liquid discharge pipe and a dispensing head having a valve controlled liquid outlet, said pipe being insertable within a container so as to extend therefrom; an air transfer pipe having a non-return valve, and an air injector therein, said injector having therein holes for admitting a proportion of air at atmospheric pressure to the compressed air stream, and atmospheric air leads to said holes from different surfaces of the injector, to admit atmospheric air during the induction of same and to provide for the by-passing of surplus high pressure compressed air when the pressure in the container has reached the predetermined safe limit before the supply of high pressure compressed air may have been cut off, an air admission control valve in said head in communication with said air transfer pipe for controlling the passage of compressed air from the head to the container; a rocking lever on the head for operating both the fuel outlet control valve and the air admission control valve; a fixed hand grip, and a trigger for actuating the rocking lever both on said head; lugs on the latter, and a pin for inserting in said lugs, for preventing operation of said valves, and a guide on the head adjacent the liquid outlet for receptacles placed below the latter.

2. Apparatus for use in delivering liquid from containers, wherein a common spring mounts the rocking lever and the trigger, a stem for the liquid outlet control valve adjacent one end of the lever, said stem having a circular groove therein, a pin for operating the compressed air admission control valve adjacent the opposite end of the lever, said pin having spaced abutment surfaces thereon projecting outwardly therefrom, the ends of the rocking lever being forked, the forks at one end having inwardly

extending pins thereon disposed in the groove in said stem and the forks in the other end passing upon said pin and between the abutments and said abutments being spaced apart sufficient to provide for lost motion between said lever and said pin.

3. Apparatus for use in the delivery of liquids from containers including a liquid discharge pipe insertable into a container from which liquids is to be delivered, an air conduit associated with said pipe for direct compressed air into the container for ejecting liquid therefrom through said pipe, a dispensing head connected to said pipe, said head having a liquid outlet and a compressed air inlet therein, valves respectively controlling said outlet and inlet, said outlet and inlet being in respective communication with said pipe and conduit, operating means for the valves operable to permit the passage of compressed air through the conduit into the container upon opening movement of the valve controlling the liquid outlet, said conduit having a non-return valve and an injector therein, said injector including a body portion having apertures therein in communication with the atmosphere for passing a proportion of air at atmospheric pressure to the compressed air stream and said apertures permitting the by-passing of surplus high pressure compressed air when the pressure in the container has reached a predetermined safe limit, before the supply of high pressure compressed air has been cut off, and said body having channels communicating with the apertures therein open through their length and ends and through more than one surface of the body of the injector.

4. Apparatus as defined in and by claim 3 wherein the injector body is fluted to define said channels, the bases of the channels communicating with the apertures in the body that constitute passages for atmospheric air and said channels being open at their sides and ends through surfaces of the body at angles to each other.

5. Apparatus as defined in and by claim 4 wherein the channels defined by the flutes are open through the side and an end of the body.

6. Apparatus for use in delivering liquid from containers including a dispensing head, a valve controlled outlet therein, a valve in said outlet, a compressed air inlet in the head, a compressed air admission valve in said head controlling passage of air therethrough, an air conduit extending from the head, means defining a venturi in said air conduit, a non-return valve in said conduit on the discharge side of said venturi, means for controlling the valves including a rocking lever on said head, a spindle mounting said lever for pivotal movement, a trigger on said spindle, and a lost motion connection between said lever and said compressed air admission valve whereby upon actuation of said trigger said outlet valve is actuated prior to the actuation of said air admission valve.

7. Apparatus as defined in and by claim 6, and spaced lugs carried by said head, said rocking lever being mounted between said lugs, a stem for said outlet valve projecting between said lugs, aligned apertures in the lugs the axes of which are disposed in the path of movement of said stem and a locking pin insertable through said apertures to be disposed in the path of movement of said stem to thereby prevent movement of the stem to open the outlet valve and thus movement

of the rocking lever and operation of the air admission valve.
